UNITED STATES PATENT OFFICE.

JOHN T. CURRAN, OF BROOKLYN, ASSIGNOR TO TIFFANY & CO., OF
NEW YORK, N. Y.

DESIGN FOR A VESSEL.

SPECIFICATION forming part of Design No. 23,558, dated August 14, 1894.

Application filed April 21, 1894. Serial No. 508,524. Term of patent 3½ years.

To all whom it may concern:

Be it known that I, JOHN T. CURRAN, a citizen of the United States, and a resident of Brooklyn, in the county of Kings and State 5 of New York, have invented a new and original Design for Vessels, of which the following, taken in connection with the accompanying drawing, is a specification.

The figure in the drawing shows a side elevation of a vessel embodying my invention.

This vessel is particularly adapted for table use.

The leading feature of my design consists in a border characterized by upper and lower 15 undulating outlines, between which are arranged panels of scroll work, and a series of fluted panels extending downward from the lower edge of the border.

A is the border which extends around the 20 upper edge of the vessel. Its upper and lower

outlines, *a* and *b* are undulating, and between them are arranged a series of panels of scroll work *c* and *d*. These panels, as shown in the drawing, are perforated, but this perforation is not an essential feature of my invention. 25 Beneath the lower edge of the border is arranged a series of downwardly extending fluted panels *e*.

What I claim, and desire to secure by Letters Patent, is—

The design for a vessel substantially as shown and described.

In testimony whereof I have signed my name to this specification in the presence of two subscribing witnesses.

JOHN T. CURRAN.
